(57) **CLAIM**

The ornamental design for a rope vise tensioner, as shown and described.

DESCRIPTION

FIG. 1 is a first perspective view of a first embodiment of a rope vise tensioner in accordance with my new design;

FIG. 2 is a top view thereof;

FIG. 3 is a bottom side view thereof;

FIG. 4 is a back side view thereof;

FIG. 5 is a front view thereof;

FIG. 6 is a left side view thereof;

FIG. 7 is a right side view thereof;

FIG. 8 is a second reference view thereof;

FIG. 9 is a first perspective view of the rope vise tensioner in accordance with my new design, with the arm in an extended position;

FIG. 10 is a second perspective view of the rope vise tensioner in accordance with my new design, with a pivotable arm in an extended position;

FIG. 11 is a first perspective view of the rope vise tensioner in accordance with my new design, with a movable structure in a retracted position and with the pivotable arm in an extended position;

FIG. 12 is a second perspective view of the rope vise tensioner in accordance with my new design, with the movable structure in a retracted position and with the pivotable arm in an extended position;

FIG. 13 is a perspective view of a second embodiment of a rope vise tensioner in accordance with my new design; and, FIG. 14 is a perspective view of the rope vise tensioner of the first embodiment in accordance with my new design, with the movable structure in a retracted position.
